UNITED STATES PATENT OFFICE.

ARNOLD LARSEN, OF CLEVELAND, OHIO, ASSIGNOR TO THE WM. GENT VENDING MACHINE COMPANY, OF CLEVELAND, OHIO, A CORPORATION OF OHIO.

APPORTIONING DEVICE.

1,327,678.

Specification of Letters Patent. Patented Jan. 13, 1920.

Application filed August 17, 1916. Serial No. 115,533.

To all whom it may concern:

Be it known that I, ARNOLD LARSEN, a subject of the King of Norway, residing at Cleveland, in the county of Cuyahoga and State of Ohio, have invented a certain new and useful Improvement in Apportioning Devices, of which the following is a full, clear, and exact description, reference being had to the accompanying drawings.

This invention relates to a device or apparatus for automatically dividing objects according to a prearranged apportionment. It is especially adaptable to coin controlled machines for dividing the receipts thereof on a percentage basis, one portion representing the amount due the proprietor of the location, for instance, and the other the revenue of the owner of the machine. Because of the peculiar adaptability to this purpose, I have elected to illustrate and describe my invention herein as a coin distributing device for incorporation in coin controlled machines. As the invention is applicable to all varieties of machines of this character, I will restrict it to no particular kind in the following description.

The general purposes of the invention are to provide a very simple, yet positively acting device for dividing objects into lots of predetermined proportions; and to provide such a device with means of adjustment whereby the proportions may be changed as desired.

Further and more limited objects of the invention will become apparent as I proceed to describe the embodiment illustrated in the accompanying drawing, and while the description will be directed to its details of construction, it will be understood that I do not limit myself to such details further than is required by the terms of the annexed claims and is rendered necessary by the state of the prior art.

In the drawing, Figure 1 represents a perspective view of the device associated with the coin tubes of a coin controlled machine, the tubes being shown in broken lines; Fig. 2 is a front elevation of the device with the face plate removed; Fig. 3 is a rear elevation of the device; Figs. 4 and 5 are vertical sections on the respective section lines 4-4 and 5-5 of each of Figs. 2 and 3; and Fig. 6 is a horizontal section on line 6-6 of Fig. 2.

The device comprises a flat body portion

1 having shallow flanges 2 projecting forwardly from its lateral edges, said flanges being turned inward at their upper ends, as shown at 2^a, along the upper edge of the body portion 1, and then vertically along the 60 sides of the reduced upper end of the body portion 1, to form a neck 3, such neck being located adjacent the right hand side of the body portion, as viewed in Figs. 1 and 2. A face plate 5, of the same general shape as 65 the body portion 1, is applied to the front of the body portion and held thereto by screws 6 which enter threaded apertures in the flanges 2. Thus a passageway is formed between the face plate and the front surface of 70 the body portion, and is of a depth from front to back slightly greater than the thickness of the coins that are intended to be used in connection with the device. The passageway is divided vertically into chutes 75 A and B of substantially the same width, by an adjustable partition strip 10, from the front of which projects, adjacent its upper end, a threaded stud 11, through a slot 12 in the face plate 5, a nut 13 being applied to the stud for clamping the partition strip in any adjusted position. A slot 14 extends throughout the lower portion of the strip, and a screw 15, which passes through the face plate and is threaded into the body 80 portion 1, reposes within the slot 14 and constitutes a guide for the partition strip.

The body portion 1 is notched upward from its lower end central of each of the chutes A and B, the notches of the respective 90 chutes being designated by the reference characters *a* and *b*. Within the upper end of the notch *a* depends a hook or abutment portion 16, of a weighted dog 17, that is pivoted upon a pin 18, which extends across the 95 restricted upper end *a'*, of the notch *a*. A pair of lugs 20 extends from the rear of the body portion 1 between the upper ends of the notches *a* and *b*, and a rock shaft 21 is journaled within alining perforations there- 100 of. This shaft is formed of a portion of a wire, one end of which is bent downward and curved forwardly through the notch *b*, to constitute a rocker arm 22. It will be seen especially upon reference to Fig. 5, 105 that this rocker arm extends forwardly through the chute B, the face plate 5 being notched at 5^b to accommodate it. It will also be observed, from Figs. 1 and 4, that the face plate is provided with a slot 5^a 110

which extends longitudinally of the chute A. The end of the wire opposite that which constitutes the rocker arm 22, is bent downward a short distance and then at right angles and parallel to the rock shaft through a vertical notch 23 in the dog 17, thereby to form an actuator 24 for such dog. It may be explained that the dog 17 is so weighted as to maintain its hook or abutment 16 normally in the chute A, and the rocker arm 22 within the chute B, as illustrated.

The face plate is provided with a series of graduations along one side of the slot 12, 15 to enable the partition strip 10 to be adjusted for the purpose of determining the proportions or percentage according to which objects fed through the device are to be divided. As shown, the device is 20 adjusted to apportion objects or coins passed therethrough on a one-fourth or twenty-five per cent. basis. In other words, when one coin is delivered through one of the receiving tubes of the machine by the device 25 of my invention, three coins will be distributed to the other as will be clearly understood from the following description of the operation of the device.

It will be assumed that a coin has been 30 deposited in the machine and that it has found its way, through the tube C, into the upper end of the passageway between the face plate 5 and the body portion 1. Dropping directly vertically into the device, the 35 coin strikes the upper and slightly rounded end of the partition strip 10 and is directed thereby into the passageway A, through which it descends until it engages the protruding hook or abutment portion 16 of the dog 17, whereon it then rests. The two succeeding coins will act in the same manner and lodge, one upon the other, upon the coin that is suspended by the dog 17, the upper edge of the last inserted coin reposing 40 slightly above the corresponding end of the partition strip 10. The next coin to be inserted will follow the course of the former coins until it strikes the upper edge of the top coin, and, because of the fact that the 45 neck 3 is offset out of vertical alinement with the chute A and toward the chute B, the present or fourth coin will strike the third coin to the left of its vertical axis (as viewed in Fig. 2) and be deflected thereby 50 over the upper end of the partition strip and into the chute B. As the coin descends through chute B it will engage the forwardly curved portion of the rocker arm 22, swinging the rocker arm rearwardly out 55 of its way and continuing downward into the tube D. The rocker arm 22, the rock shaft 21, and the actuator 24 being rigidly connected together and operatively engaged with the dog 17, the rearward swinging of 60 the rocker arm will move the dog in a corre- 65

sponding direction to withdraw the hook or abutment portion 16 from beneath the bottom or first coin, thus releasing the coins in chute A and allowing them to descend through the tube E.

From the fact that the distance between adjacent graduations on the face plate is substantially equal to the diameter of a coin, it will be seen that when the partition strip is adjusted upwardly successively from one 75 to the other of the graduations, the device illustrated herein will operate to divide the coins on a one-half, one-third, one-fourth, or one-fifth basis.

Having thus described my invention, so what I claim is:—

1. A device of the character set forth comprising a body portion having a through passageway, an adjustable partition strip dividing said passageway into a main chute 85 and a branch chute, the body portion having an inlet passage which is offset somewhat from the central axis of the main chute toward the branch chute, a pivotally supported member depending alongside the main chute and having an abutment portion which bisects the same, a second member which normally reposes within the branch chute and is adapted to be swung therefrom by an object passing through the 95 branch chute, and operative connections between said members whereby such movement of the last mentioned member will withdraw the abutment of the former member from the main chute.

2. A device of the character set forth comprising a body portion having a passageway, an adjustable partition for dividing said passageway into a main and branch chute, the passageway having an 105 inlet through which objects are introduced into the passageway in a position to be deflected by the partition normally into the main chute, a gravity dog pivotally supported from the body portion and having 110 an abutment portion which normally reposes within the main chute and acts to temporarily arrest objects which are deposited therein, a rock shaft supported adjacent the body portion, a rocker arm secured to the 115 shaft and reposing normally within the branch slot in a position to be engaged by objects passing therethrough and swung thereby from such slot, and an actuator secured to the rock shaft and operatively 120 connected to the aforesaid dog for swinging said dog in a direction to withdraw its abutment portion from the main chute.

3. A device of the character set forth comprising a casing having side walls that are 125 spaced apart a distance slightly greater than the thickness of a given coin, said casing inclosing a passageway, a partition strip extending longitudinally of the passageway and dividing the same into a main and a 130

branch chute, the casing having an inlet at its upper end that is more nearly in alignment with the main chute than the branch chute, the casing having openings in one of its side walls, one of said openings being substantially central of each chute, bearing members carried by the casing adjacent said openings, a rock shaft journaled within said bearing members, a gravity dog pivotally supported within one of said openings and having an abutment portion which extends abruptly across the main chute when the dog is in normal position, a rocker arm secured to the rock shaft and depending through the other opening into the branch chute, and an actuator carried by said rock shaft and operatively connected to the aforesaid dog whereby said dog will be swung to withdraw its abutment from the main chute when an object passing through the branch chute engages and moves the aforesaid rocker arm.

4. A device of the character set forth comprising a body portion having comparatively shallow flanges projecting forwardly from its lateral edges, said flanges approaching each other at their upper ends along the upper edge of the body portion to within a distance substantially equal to the diameter of a given coin, a face plate applied to said flanges and spaced thereby from the body portion a distance slightly greater than the thickness of said coin, a partition strip centrally located between the aforesaid flanges, means for adjusting said strip longitudinally, and for clamping it in any adjusted position to the structure, the strip thus di-

viding the space inclosed by the face plate and body portion into two chutes, a member pivoted to the body portion and having an abutment which normally reposes within one chute to obstruct the passage of coins therethrough, and a rocker arm normally reposing within the other chute, operative connections between said rocker arm and the aforesaid member whereby said member is withdrawn from its respective chute to release the coins sustained thereby when the rocker arm is engaged and moved by a coin passing through its respective chute. 50

5. A device of the character set forth comprising a body portion having a through passageway, a partition dividing said passageway into a main chute and a branch chute, the body portion having an inlet passage, a movable member bisecting the main chute, a second member which normally hangs vertically and has a cam portion reposing within the branch chute so that an object passing through the branch chute will engage said cam portion and swing the second member laterally from its normal vertical position, and interengaging connections between said members whereby such movement of the last mentioned member will positively withdraw the former member from the main chute. 55 60 65

In testimony whereof, I hereunto affix my signature in the presence of two witnesses.

ARNOLD LARSEN.
